HOIST CONTROL

William C. Anthony and Lester Wachter, Streator,
Ill., assignors to Anthony Company, Streator,
Ill., a corporation of Illinois

Application June 1, 1931, Serial No. 541,399

15 Claims. (Cl. 298—22)

This invention relates to a hoisting mechanism and to means of controlling the same.

It has for one object to provide, in connection with a hoist, means for causing a "shaking" effect. Such shaking effect may be caused at one end of the excursion of the hoist.

Another object is to provide an automatic means in connection with a hoist, which may be used to raise a dumping body, whereby the body is jerked repeatedly at the upper or raised position.

Other objects will appear from time to time in the specification and claims.

Our invention is illustrated more or less diagrammatically in the accompanying drawings, wherein:—

Figure 1 is a longitudinal vertical cross section, showing the body in the raised position;

Figure 2 is a longitudinal vertical cross section showing a modified form of the invention;

Figure 3 is a cross sectional detail on an enlarged scale, showing a portion of the controlling mechanism of Figure 2; and

Figure 4 is a view similar to Figure 3, showing a modified form.

Like parts are designated by like characters throughout the specification and drawings.

While the hoisting mechanism and the controls therefor are not limited to use in connection with a vehicle, they may be conveniently so used and the invention is, therefore, illustrated in one form as applied to the hoisting mechanism for a dumping body, which is mounted upon an automotive truck. A indicates generally the vehicle frame. A¹ is an axle. A² is a wheel, A³ is a cross member having bearing supports A⁴. A⁵ is a frame member having a flange A⁶. A⁷ is a cross frame member which may be made up of one or more parts. A⁸ is an additional cross frame member. The members A⁷ and A⁸ support the hydraulic hoisting mechanism. A⁹ is a track, resting upon flange A⁶.

B is a body provided with downwardly projecting members B¹ which, by means of pins B², are pivotally supported in the members A⁴ so that the body may be swung up and down about the members B². The body B may have one or more stiffening and supporting frame members B³ B⁴ and may carry a track B⁴ which, as here shown, is a channel member, although it might be of any suitable structure.

C is a lever assembly, preferably pivoted at C¹. At its upper end the assembly carries a roller C² which lies within and is engaged by the track B⁴. The lever assembly C is provided with one or

more inclined roller contacting faces C³ the use of which will be described below.

D is a transmission housing within which drive members are mounted which are driven by the engine of the vehicle. A driven shaft D¹ protrudes from the housing D and through a universal D² drives a shaft D³. The latter, through a universal D⁴, drives the shaft D⁵ of a pump which is mounted within the housing D⁶. The pump is preferably a rotary pump, or it may be a gear pump or any other suitable means adapted to circulate the fluid in the hydraulic system. The pump housing D⁶ may be integral with a housing D⁷ which contains a sump D⁸ and a passage D⁹ through which the fluid moves from the pump to the cylinder. The sump may have an open top and may be covered by a removable cover D¹⁰.

Joined to the housing D⁷ is a fitting E to which the cylinder E¹ is fastened. A passage E² within the member E communicates with the passage D⁹ within the member D⁷. It is provided with a ball check valve E³ which is normally seated by the spring E⁴ and also by pressure within the cylinder E¹. It may be unseated by pressure from the passage D⁹. An outlet passage E⁵ is provided in the member E, and it communicates with a passage E⁶ which leads to the sump D⁸. The passage is normally held closed by a ball check valve E⁷ which is seated by a spring E⁸ and by pressure within the cylinder E¹. Means for unseating the valve E⁷ comprises a rod E⁹ having a flattened portion E¹⁰. The rod E⁹ is provided with a lever E¹¹ to which a link E¹² is pivotally fastened. By means of the lever and link the rod E⁹ may be rotated to move the ball valve E⁷ from its seat to open the passage E⁵ and permit escape of fluid from the cylinder. The outer end of the cylinder is closed by a member E¹³ which is perforated and provided with a packing E¹⁴ and a packing gland E¹⁵ which is provided with lugs E¹⁶ adapted to be engaged and held in fixed position by screws E¹⁷ which are also engaged in the member E¹³. The outer end of the cylinder is held in position upon the cross frame member A⁸ by a U-bolt E¹⁸ which passes through the member A⁸ and is engaged by nuts E¹⁹. E²⁰ is a by-pass running from the outer end of the cylinder to the space E⁵ to return fluid which has passed beyond the piston.

The cylinder is provided with a piston F. The piston may be of any suitable construction but as shown is made of two circular metal plates which are held together and engaged between them is a leather cup F¹. F² is a piston rod pro-

vided with a reduced portion F^3 which is threaded at its outer end. The piston members, including the cup F^1 , are positioned on the reduced portion F^3 and are held in position thereon by the 5 nut F^4 .

A perforation G is formed through the several members which make up the piston. Mounted within this perforation G is a sleeve G^1 having a collar or flange G^2 at one end and an enlargement G^3 at its other end. This enlargement is 10 tapered along a portion of its exterior as at G^4 and is provided with a valve seat G^5 . G^6 is a poppet valve adapted to be seated in the seat G^5 . It is fastened to a stem G^7 which lies within and 15 is adapted to move within the sleeve G^1 . G^8 is a stop member fastened on the stem G^7 . At one end the stem G^7 carries a contact member G^9 . A large spring G^{10} is positioned about the sleeve and about the valve stem. At one end the spring 20 engages the stop G^8 which is fixed to the stem G^7 and at its other end the spring bears against the piston F . G^{11} is a relatively smaller spring positioned about the stem G^7 , bearing at one end against the flange G^2 on the sleeve G^1 and at 25 its other end against the stop G^8 on the stem G^7 .

In the form shown in Figure 1, instead of the piston construction above described for providing shaking of the body at the raised position, a different construction is illustrated. A control member H is provided by means of which the 30 clutch may be manipulated into and out of engagement so that the pump drive may be connected and disconnected. The lever H is normally held in engaging position by a spring H^1 which thus holds the clutch in engagement to drive the pump shaft. A rod H^2 is fastened to the lever H at one end and at its other end it passes through one end of a bell crank H^3 . A cushioning spring H^4 is provided about the outer end 35 of the rod H^2 and is held in adjusted position thereon by a nut H^5 and a washer H^6 . The bell crank H^3 is pivoted as at H^7 . It is laterally bent as at H^8 and carries on the laterally bent portion an adjustably positioned weight H^9 . A spring 40 H^{10} may be attached to the bell crank H^3 below its pivot point, being fastened at one end on the housing D^7 and adjustably attached to the bell crank H^3 as shown. Either the spring H^{10} or the weight H^9 may be used; ordinarily one will be 45 enough. Each of them tends to move the crank H^3 into the position shown in Figure 1, and thus to move the rod H^2 to the left as shown in Figure 50 1, so as to free the clutch lever H . Thus this lever can be moved into the engaging position by the spring H^1 .

I is a rod attached to the bell crank H^3 below its pivot point and extending to and preferably through a cross head I^1 which is mounted at the outer end of the piston rod F^2 . At its outer end 55 the rod I is threaded as shown in Figure 1, and provided with one or more nuts I^2 . The cross head is provided with rollers I^3 adapted to run along the flange A^6 of the track A^5 . Other rollers, which in the showing of Figure 1 are masked by the rollers I^3 , are provided to engage the inclined face or faces C^3 of the lever assembly C.

The modified form shown in Figure 4 differs from the valve construction of the other figures. In the form of this figure the piston is built up, 70 being formed of the member J which has a flange-like extension J^1 on its outer edge and an internal cylindrical extension J^2 . A cup-like member J^3 which may be of leather or other suitable material, is held to the member J by a disk or plate J^4 . The member J^4 is perforated

at J^5 and the cup J^3 is perforated at J^6 . These perforations are in line with the hollow bore of the member J^2 .

K is a valve stem having a tapered enlarged valve portion K^1 . The stem is positioned within the cylindrical portion J^2 and extends outwardly from it at each end. The head or valve portion K^1 may be seated against the disk J^4 as shown in Figure 4. The outer end of the valve stem K may contact the member E^{13} which closes the 10 cylinder. A pin or other stop member K^2 is positioned in the stem K. A relatively large, generally helical spring K^3 having a tapered end is positioned about the valve stem K and bears at one end against the piston J and at the other 15 against the stop K^2 . A relatively smaller and preferably generally helical spring K^4 is positioned about the stem K and may bear at one end against the plate E^{13} as indicated in Figure 4 and at the other end bears against the stop K^2 . 20

It will be realized that whereas we have here- 25 with shown and described a practical operative device, nevertheless many changes might be made in the size, shape, number and disposition of parts without departing from the spirit of our invention and we wish, therefore, that our showing be taken as in a sense diagrammatic. In particular, the construction shown in Figures 2 and 3 might be modified by having the element G^3 separate from the sleeve G^1 . If this were the case, the interior 30 bore of the element G^3 would be of substantially the same diameter as the stem G^7 and would contact it. Thus the element G^3 would slide upon the stem G^7 and the sleeve G^1 would merely contact the end of the element G^3 . 35

The use and operation of our invention are as follows:

In the form shown in Figure 1, when it is de- 40 sired to dump or tip the body, the clutch is engaged so that the pump is driven and pressure is forced from the pump through the passage D^9 into the cylinder E^1 , moving the piston outwardly toward the right as shown in Figure 1. As the piston approaches its outward limit, the cross head I^1 engages the nut I^2 on the rod I and pulls 45 it, thus rotating the bell crank H^3 , swinging its lower arm to the right against the resistance of spring H^{10} , and moving the rod H^2 in the same direction to move the lever H of the clutch and so to disengage the pump. As soon as the pump 50 operation is stopped, the body descends. With a very slight movement in this direction the cross head has moved again to the left as shown in Figure 1, sufficiently to be out of contact with the nut I^2 on the rod I. Thus the rod is no longer held to the right and the spring H^{10} or the lever H^9 , or both of them, if they are both used, move the lower end of the bell crank H^3 to the left 55 and remove the tension from the rod H^2 and permit the spring H^1 to move the clutch lever H into the engaging position. When this occurs the pump starts at once and the piston is moved again to the full outer limit of its excursion. The back and forth movement will occur automatically and will result in relatively slight back 60 and forth movement of the cross head and will continue automatically until the operator so manipulates the controls as to permit a continued escape of fluid from the cylinder. This is accom- 65 plished by moving the lever E^{11} to rotate the shaft E^9 so that the flat portion E^{10} of that shaft moves out of engagement with the ball valve E^7 , and thus the rounded portion of the shaft E^9 engages the ball and raises it from its seat, per- 70 mitting discharge of the fluid from the cylinder 75

and consequently permitting inward movement of the piston and lowering movement of the body.

In the form of the invention shown in Figures 2 and 3, the operation of the pump need not be interrupted. As the piston moves toward the outer limit of its excursion, the member G⁹ contacts the cylinder head E¹³ and the valve G⁴ is unseated, being moved into the position shown in Figure 3. In this position no leakage through the piston occurs. Thus after the member G⁹ strikes the cylinder head E¹³ some further movement of the piston will occur, unseating the valve and compressing the spring G¹¹. When that spring is fully compressed or when it is sufficiently compressed, it will expand and drive the sleeve G¹ with the member G³ to the left, unseating it and thus opening the passage G through the piston. Sufficient leakage can then occur through the piston to permit reverse movement of the latter and thus to cause a slight lowering of the body. This reverse movement of the piston is usually sufficient to move the member G⁹ out of contact with the cylinder head E¹³. As soon as the spring G¹¹ is relieved of compression, it seats the sleeve G¹ and again closes the opening G¹³ to prevent discharge of fluid past the piston. The spring G¹⁰ also is relieved of compression since the member G⁹ no longer contacts the cylinder head E¹³ and thus the valve stem G⁷ with the valve is moved to the right, seating the valve in the seat G⁵. As soon as these parts are seated, since the movement of the pump continues, pressure builds up and the piston is moved again to the right. The member G⁹ again contacts the cylinder head and the same cycle of movements is repeated. Thus, by providing an automatic means in the piston, the movement of the latter is automatically controlled so that it moves backwards and forwards throughout a limited amount of travel. This will occur until the operator operates the controls to open the main discharge from the cylinder as above described.

It will be seen thus that in the two forms of our invention we have provided means for giving the piston limited and relatively rapid reciprocation at or near the outer end of its travel. This produces upon the body a shaking or rattling action which is frequently important in helping to discharge sticky or other loads which tend to adhere to or remain in the body.

The use and operation of the form shown in Figure 4 are generally the same as that of the form shown in the earlier figures. The small spring A⁴ is slightly stronger than the larger spring K³ but is overcome by the combined forces of the larger spring and the oil pressure against the valve head K¹. As the piston advances or moves outwardly, that is, to the right as shown in Figure 4, the small spring strikes the cylinder head and is compressed but it is not strong enough to force open the valve against the opposition of the spring K³ which tends to seat the valve and the force of the oil pressure within the cylinder against the valve K¹. As the piston continues to move the outward end of the valve stem K strikes the cylinder head and the valve is forced open. When this occurs, oil passes through the valve and lowers the pressure to the left of the piston, thus allowing the small spring to overcome the force of the large spring, which opens the valve further and permits the more rapid discharge of oil through it. When this occurs pressure is not sufficient to hold the piston to the right as shown in Figure 4 and it then moves backward and as soon as the compression on the large spring K³ is sufficiently

reduced, it may expand and thus closes the valve and permits the cycle of operations to be repeated.

We claim:

1. In combination with a receptacle, means for moving the same from loading to dumping position, and automatic means, enclosed within a part of the moving means, the moving means, adapted to cause the latter to give the body back and forth movement through a distance less than its maximum travel. 10

2. In combination with a receptacle, means for moving the same from loading to dumping position, and automatic means, enclosed within a part of the moving means, the moving means, adapted to cause the latter to give to the body 15 repeated back and forth movement through a distance less than its maximum travel.

3. In combination with a receptacle, means for moving the same in an arc from loading to dumping position, and automatic means, enclosed within a part of the moving means, the moving means, adapted to cause the latter to give to the body back and forth movement throughout a limited 20 arc, less than the arc of movement from loading to dumping position. 25

4. In combination with a receptacle, a dumping means therefor, adapted to move the receptacle from a loading position to a dumping position, and automatic means enclosed within a part of said dumping means for causing said dumping 30 means to move said receptacle rapidly repeatedly between said dumping position and a position intermediate the dumping position and the loading position.

5. In combination with a receptacle, a dumping 35 means therefor, and automatic means for shaking said receptacle in the dumping position, said means including an automatic reversing mechanism for said dumping means enclosed within a part of said dumping means, whereby the latter is caused to fluctuate back and forth repeatedly between positions near the upper limit of its excursion. 40

6. In combination in a tipping mechanism, a receptacle, tipping means for it, and automatic means enclosed within a part of said tipping 45 means adapted to cause said tipping means repeatedly to reverse its direction of movement, at one end of its main excursion, without returning to the other end of its main excursion. 50

7. In combination in a tipping mechanism, a receptacle, hydraulic means for tipping it, and automatic means enclosed within a part of said tipping 55 means adapted to cause said hydraulic tipping means repeatedly to reverse its direction of movement, at one end of its main excursion.

8. In combination with a receptacle, an hydraulic mechanism for tipping the same, said mechanism including a piston adapted to move in said piston for repeatedly reversing the direction of movement of the piston, while retaining it near one end of its main excursion. 60

9. In combination in a hoisting mechanism, adapted normally to move through a given excursion, and automatic means for repeatedly reversing the direction of movement of the hoisting means at one end of its main excursion, said means including a piston and a valve in said piston, adapted to be opened automatically by movement of the piston, in combination with means for closing said valve automatically upon reverse movement of the piston. 65

10. In combination in an hydraulic mechanism, a cylinder, a piston therein, means for supplying 70

fluid under pressure to one side of the piston to move it, a valve in the piston, two springs positioned to act upon the valve, one normally tending to seat the valve and another tending, when compressed, to unseat the valve, the last mentioned spring being compressed as the piston is moved by fluid pressure within the cylinder.

11. In combination in a hoisting mechanism, adapted normally to move through a given excursion, and automatic means for repeatedly reversing the direction of movement of the hoisting means at one end of its main excursion, said means including a piston and a valve in said piston, adapted to be opened automatically by movement of the piston, in combination with means for closing said valve automatically upon reverse movement of the piston, said closing means including a spring and means for compressing it in response to movement of the piston in the raising direction.

12. In combination in a hoisting mechanism, adapted normally to move through a given excursion, and automatic means for repeatedly reversing the direction of movement of the hoisting means at one end of its main excursion, said means including a piston and a valve in said piston, adapted to be opened automatically by movement of the piston, in combination with means for closing said valve automatically upon reverse movement of the piston, said valve including a seat and two closing members movable with respect to each other, and each movable with respect to the seat.

13. In combination in a hoisting mechanism, adapted normally to move through a given excursion, and automatic means for repeatedly reversing the direction of movement of the hoisting means at one end of its main excursion, said means including a piston and a valve in said piston, adapted to be opened automatically by movement of the piston, in combination with means for closing said valve automatically upon reverse movement of the piston, said valve in-

cluding a seat and two closing members movable with respect to the each other, and each movable with respect to the seat, and spring means for moving said valve members to close them when free to do so.

14. In combination in a hoisting mechanism adapted normally to move through a given excursion, and automatic means for repeatedly reversing the direction of movement of the hoisting means at one end of its main excursion, said means including a piston and a valve in said piston, adapted to be opened automatically by movement of the piston, in combination with means for closing said valve automatically upon reverse movement of the piston, the valve in said piston comprising a valve assembly of two relatively movable valve closing members, means for opening one in direct response to movement of the piston and yielding means for opening the other in response to movement of the piston.

20

15. In combination in a hoisting mechanism, adapted normally to move through a given excursion, and automatic means for repeatedly reversing the direction of movement of the hoisting means at one end of its main excursion, said means including a piston and a valve in said piston, adapted to be opened automatically by movement of the piston, in combination with means for closing said valve automatically upon reverse movement of the piston, the valve in said piston comprising a valve assembly of two relatively movable valve closing members, means for opening one in direct response to movement of the piston and yielding means for opening the other in response to movement of the piston, said yielding means comprising a spring effective upon one of the valve members and adapted to be compressed by movement of the piston and when so compressed to move the valve member upon which it is effective to open it.
